(57) CLAIM

The ornamental design for a jug, as shown and described.

DESCRIPTION

FIG. 1 is a side elevation view of a jug showing our new design;

FIG. 2 is an opposing side elevation view thereof;

FIG. 3 is a front elevation view thereof;

FIG. 4 is a rear elevation view thereof;

FIG. 5 is a bottom plan view thereof;

FIG. 6 is a top plan view thereof;

FIG. 7 is a front perspective view thereof; and,

FIG. 8 is a rear perspective view thereof.

The broken lines in the drawings showing of the jug illustrate the portions of the jug that form no part of the claimed design.

The stipple shading in the drawings illustrate a constricting appearance.
